DERAILER

Application filed November 1, 1927. Serial No. 230,259.

This invention relates to derailers for railway vehicles more particularly to derailers of the type which are permanently fixed to a rail and adapted to be moved into and out of 5 railing position in accordance with service requirements.

It is among the objects of this invention to provide a derailer of simple, compact and durable mechanical construction which shall 10 embody a minimum number of operating parts and which is especially designed to be efficient in its function of derailing vehicles passing thereover.

Another object of the invention is to provide 15 a derailing device which shall be designed to support the weight of a vehicle on the rail with which it cooperates and to receive the thrust on its supporting base in a manner to prevent relative displacement of 20 the derailing member when the latter is subjected to the forces acting upon it.

Another object of the invention is to provide 25 a derailing device which shall be rendered operative or inoperative by the operation of a lever and which when inoperative is placed in position to prevent interference with the vehicles passing over the rail.

These and other objects will become more apparent from a consideration of the accompanying drawings in which like reference 30 characters designate like parts and in which Fig. 1 is a side elevational view of a derailer embodying the principles of this invention and illustrating the derailing member in its 35 operative or raised position; Fig. 2 is a similar view showing the derailing member in its inoperative or down position; Fig. 3 a top plan view of the derailer shown in Figs. 1 and 2; Fig. 4 a sectional elevational view 40 taken along the line IV—IV, Fig. 3 and Fig. 5 a sectional elevational view taken along the line V—V, Fig. 4.

Referring to the several figures of the drawings the structure therein illustrated 45 comprises a derailer embodying a base generally designated at 1 having flanges 2 (Fig. 3) provided with openings 3 for receiving spikes or bolts by means of which the base is firmly secured to the rail supporting ties. 50 The portion of the base adjacent the rail is

formed of a relatively heavy section of metal 4 (Figs. 2 and 5) having inclined seating portions 5, 6, 7, and 8 in spaced apart relation as shown in Fig. 4. The portion 4 is further provided with an upwardly projecting lug 10 55 having an opening 9 therein for receiving the pivot bolt of a link 11 which connects a derailing member 12 with the base 1.

The derailing device consists of a track portion 13 which is adapted to seat on the rail 14 with which it cooperates to derail a vehicle passing thereover. The track 13 is provided with an incline 15 which connects the upper level or plane of the derailing member with the top of the rail 14 and functions to lift the 60 tread of a wheel passing over the rail. Adjacent the lifting track 13 is a depressed web portion 16 to provide clearance for the flange of the wheel. A flange member 17 is formed integrally with the web 16 and track portion 70 13 and is of such angularity as to constitute a divergent path for the wheel to derail the vehicle.

The derailing member is provided with a lug which is pivotally connected to the link 75 11 to maintain proper spaced relation of the derailing member with its supporting base when the former is subjected to movement in a manner to be hereinafter described.

The derailing member 12 is further provided with seating portions complementary in shape to the seats 5, 6, 7, and 8 of the base, which are adapted to seat on the latter when the derailing member is in the position shown in Fig. 1 which is the derailing position. In 80 this position and by virtue of the form and location of the engaging seating surfaces, the derail 12 is adapted to resist the thrust imposed upon it by the force of a wheel passing over the derailing member 12 without stressing any weak portions of the derailer and without the possibility of displacing the derailing member from its operative position on the rail.

For this purpose a depending lug 19 is provided on one side of the derailing member which cooperates with a slotted portion 20 of the base, the bottom of which constitutes the seat 8 illustrated in Fig. 4. The purpose of 95 the slotted engagement with the lug 19 and 100

slot 20 of the derailing member and base respectively, is to take up end or side thrust which may be imposed on the derailer, particularly when a vehicle passes over the rail 5 in the reverse direction, that is, in the direction opposite to that for which the derailer is designed to operate.

The derailing member 12 is provided with a portion 21 terminating in a transverse rib 10 22 from which a pair of guide arms 23 are projected and which is further provided with downwardly depending lugs 24. The guide arms 23 pass underneath an enclosed portion 25 of base 1 and project through slotted 15 openings formed in the rear wall 26 of the enclosed member, these openings constituting guides for properly directing the movement of the derailing member 12.

The lugs 24 are provided with openings 20 for receiving pivot bolts 27 by means of which a yoke or lever portion 28 is pivotally connected, this lever being the operating lever which may be either mechanically or manually operated in any suitable manner 25 to raise and lower the derailing member on its base.

As previously explained, the base 1 is secured on the cross ties of a rail with the end portion 4 of the base adjacent the web of the 30 rail 14. To further provide against displacement of the base it may be desired to employ a pair of straps 30 having flanged ends 31 for engaging the base of the rail and a flanged end 32 that engages the rear of the base as 35 shown in Figs. 1 and 2. These straps are provided with perforations corresponding to the opening 3 in the flange 2 of the base and are secured in their proper position on the railway ties at the same time when the base is 40 fastened in the manner explained above.

In the operation of the device the derailing portion 12 is normally in its operative position which is that shown in Fig. 1, such devices being usually located on a portion of 45 the rail beyond which it is dangerous for vehicles to pass. This is the portion at which the base is firmly secured, but since it is at times necessary to permit the passage of vehicles beyond the portion of the rail on which 50 the derailer is located, the derailing member 12 may be displaced or moved to its inoperative position by means of lever 28 which is actuated to withdraw the derailing member 12 from the rail and in so doing the cooperating 55 engaging seats of the derailer and base members separate without any interference, the seating portions being particularly shaped for this purpose. In its disengaging movement the derailing member 12 slides 60 from the top of the rail and moves rearwardly, the guide arms 23 functioning to maintain the proper position of the member 12, and link 11 connecting the member 12 and base 1. 65 assures a fixed spaced relation of these parts

for any position of the member 12 on its supporting base.

When the derailing member 12 is in its inoperative or lowered position as shown in Fig. 2, it is entirely out of the way of vehicles 70 passing over the rail 14 and this is made possible, within the limits of the space permitted by the height of the rail, by the pivotal link connection and the guide arms 23.

It is evident from the above description 75 of this invention that a derailing device made in accordance therewith, is adapted to be located on the rail with which it cooperates during its derailing action and to be further supported on its base in such a manner as to 80 guard against displacement when the force of derailing is exerted thereon. It is further evident that the derailer hereinbefore illustrated and described comprises a simple design which is practical, durable and relatively 85 inexpensive to manufacture, and that the actuating mechanism is designed to be efficient in its movement of the derailer to its operative and inoperative positions.

Although one of the embodiments of this 90 invention has been herein illustrated and described, it will be obvious to those skilled in the art that various modifications may be made in the details of construction and in the design and arrangement of the several cooperating parts without departing from the principles herein set forth.

We claim:

1. A device for derailing railway vehicles comprising in combination a base member, a derailing member and a link pivotally connected to said members, said base member having a seating portion for supporting said derailing member in its operative position and being further provided with a guide, and said derailing member having a seat complementary to the shape of the seat of said base and a guide arm adapted for cooperative engagement with the guide of said base.

2. A device for derailing railway vehicles comprising in combination a base member adapted to be secured to one or more railway ties, and a derailing member adapted to be supported on the top of a rail, said base and derailing member having a plurality of complementary shaped seating faces in spaced relation for receiving the thrust imposed on the derailing member when subjected to use.

3. A device for derailing railway vehicles comprising in combination a base member adapted to be secured adjacent a rail and having a slotted seating portion therein, and a derailing member adapted to be supported on the top of the rail and having a depending lug member adapted to engage the slotted portion of said base, said base and derailing member being provided with complementary shaped seating portions.

4. A device for derailing railway vehicles comprising a base having a plurality of angu- 130

larly shaped seating faces, a derailing member adapted to be supported on the top of a rail and having seating portions complementary in shape to the seating faces of said base, 5 and a spacing link pivotally connected to said derailing member and base to maintain same in proper spaced relation for any position of the derailing member.

5. A device for derailing railway vehicles 10 comprising in combination a base member, a derailing member and a link pivotally connected to said members, said base member having guides provided therein and said derailing member being provided with guide 15 arms which are disposed in the guide of said base and an operating lever pivotally connected to the derailing member for subjecting the latter to movement to produce cooperative engagement of the derailing member 20 with a rail, said link being operative to maintain the proper spaced relation of the derailing member and base for any position of the derailing member.

6. A device for derailing railway vehicles 25 comprising in combination a base member and a derailing member having complementary shaped seating faces of such shape as to absorb thrust tending to move the derailing member from its operative position when in 30 engagement with a rail, guide means for directing the movement of said derailing member, and a spacing link pivotally connected to the derailing member and base which is adapted to disengage the seating faces of 35 said members when the derailing member is subjected to movement.

7. A device for derailing railway vehicles comprising in combination a base member and a derailing member and a link pivotally 40 connected to said members to maintain the same in their proper cooperative relation, said base member being provided with guides and said derailing member with guide arms cooperatively disposed in said guides, said 45 guide arms constituting a support for the derailing member when the latter is in its derailing position in engagement with a rail.

In testimony whereof, we have hereunto set our hands.

50 GEORGE H. FRAZIER.
ALBERT E. HERROLD.
